CLOSURE AND APPLICATOR ROD
ASSEMBLYStephen T. Moreland, Toledo, Ohio, assignor to
Owens-Illinois Glass Company, a corporation
of Delaware

Application October 7, 1941, Serial No. 413,999

2 Claims. (Cl. 15—140.3)

My invention relates to improvements in container closures having an applicator rod attached thereto, to be used on containers for medicines, cosmetics or the like from which the contents are to be used in more or less small quantities.

At the present time, closures having applicator rods attached thereto, usually have the rod attached in a rigid manner. When the closure is removed from the container, the applicator rod, which was partially submerged in the liquid contents of the container, is simultaneously withdrawn and a portion of the contents of the container adheres to the lower end of the applicator rod.

In the instance where medicines such as mercuriochrome, iodine, collodion or the like, are used, a small quantity of the liquid adheres to the lower end of the rod and is applied to the skin or cut of the user as needed. By having the rod rigidly fastened to the closure, the application of the medicine is sometimes very painful due to the person's inability to touch the surface of the skin lightly.

An object of my invention is to provide a closure with an applicator rod attached in such a manner that the rod is more or less a floating rod and therefore only the weight of the rod bears on the surface to which the medicine or the like is applied.

Another object is to provide a closure with an applicator rod round in cross section attached in a circular well of the closure in which the diameter of the rod is less than the internal diameter of the well, thus giving the rod free movement within the attaching well.

Another object is to provide a closure with an applicator attached in a well of the closure, in which the upper end of the rod is upset or enlarged and is snapped over protuberances formed on the internal surface of the well, thus holding the applicator rod in place.

Another object is to provide a closure with an applicator rod, having an enlarged end, that is attached thereto in a depending well of the closure, the well having internal protuberances formed short of the closed end of the well providing a space larger than the enlarged end of the applicator rod, thus permitting axial movement of the rod.

Other objects will be in part apparent and in part pointed out hereinafter.

In the drawing:

Fig. 1 is a vertical sectional view of the closure with the applicator rod attached.

Fig. 2 is a bottom plan view of the closure with the applicator rod shown in cross section.

Fig. 3 is a vertical sectional view of the closure with the applicator rod shown in elevation and detached from the closure.

Fig. 4 is a side elevation of a modified form of the applicator rod.

Fig. 5 is a similar view of a further modified form.

I have shown a molded cap or closure 10, formed of a material such as urea formaldehyde or the like, having internal threads 11 formed therein to receive external threads formed on the neck of a container (not shown).

The cap has a depending skirt or vertical wall 12 and an outer or horizontal wall 13. Depending from the inner side of the horizontal wall 13 is an annular projection 14 concentric with the skirt 12, having a cavity or well 15 terminating in a bottom wall 16. Formed internally of the wall of the cavity 15 and spaced a short distance from the bottom wall 16, is a series of protuberances 17. I have shown four of these protuberances 17, but two or more will perform the same function.

The applicator rod 18 has an enlarged head 19 formed on the upper end thereof. In assembling the closure and the applicator rod together, the head 19 is placed in the cavity 15 of the projection 14 and the head of the rod is snapped past the protuberances 17. The protuberances then hold the rod from falling out of the cavity 15.

The outside diameter of the rod 18 is slightly less than the distance between diametrically opposed pairs of the protuberances 17 and the outside diameter of the head 19 is greater than the distance between said protuberances. The diameter of the cavity 15 of the projection 14, is greater than the outside diameter of the head 19.

The protuberances 17 formed in the cavity 15, are spaced from the bottom thereof a distance slightly greater than the vertical cross sectional dimension of the head 19 on the rod 18.

As may be readily seen in Fig. 1, the applicator rod 18 is very loosely mounted in the cavity 15. However, it is held therein in such a manner that it cannot become dislodged accidentally. As may be seen by the dash and dotted lines in Fig. 3, the rod 18 is free to move sideways when the applicator is used.

In applying the contents of a container to which the closure is applied, it may readily be seen that a very slight pressure is applied to the surface of the skin of the person to be treated. In the instance of an open cut, placing of the applicator

rod in one end thereof and drawing the rod the length of the cut, the rod will follow the contour of the cut with very little help from the person using the applicator.

In Figs. 1 and 3 I have shown the applicator rod to be tubular and with a head 20 formed on the lower end of the rod similar to the upper head 19. By having heads 19 and 20 formed on either end of the applicator 18, creates a much simpler operation in the assembling of the cap and applicator whether it be an automatic, or manual, operation.

The lower head 20 also serves as a means to hold more liquid on the rod when said rod is removed from the container. The hollow applicator 15 also has a capillary action in applying the contents of the container.

Fig. 4 shows a modified form of applicator 21 having an enlarged head 22 formed at the top of the applicator while the lower end does not have any enlargement. The head 22 is snapped into position in the well 14 in the same manner in which the head 19 is inserted. The applicator 21 is tubular.

Fig. 5 shows another modified form of applicator 23 having enlarged heads 24 formed on both ends thereof. However, the applicator 23 is a solid rod and the liquids of the container to which the closure is applied, may only adhere to the outside surface of the applicator. This does not have a 30 capillary action as do the other forms of applicators.

Modifications may be resorted to within the spirit and scope of the appended claims.

I claim:

1. In combination, a closure including a top portion, a depending attaching skirt at the margin of the top portion, an annular depending wall axially of and concentric with said skirt and disposed within said closure to form a well having an open end, protuberances internally of said well, said protuberances being spaced from the open end of the well and extending radially inward from the wall, and an applicator rod having a head at one end for reception in said well, said rod being of less diameter than the well and said head being of slightly greater diameter than the distance between certain of the protuberances and less than the diameter of the well, said head also being of less axial length than the distance between the protuberances and bottom of the well.

2. The combination of a closure cap and an applicator rod, said cap including a vertical depending skirt to engage a neck of a container, a horizontal wall at the upper end of said skirt, an annular projection internally of said horizontal wall providing a vertical cylindrical well, and a series of protuberances formed internally and radially of said well and the applicator rod having an enlarged head at one end thereof, said head inserted in the well and beyond the protuberances, the head being adapted to rest upon the protuberances and being of less diameter than that of the well above the protuberances, and that portion of the rod within the well being of less diameter than the diameter of an imaginary circle contacting the innermost points of the series of protuberances.
